US0D1039120S

(12) **United States Design Patent** (10) **Patent No.:** **US D1,039,120 S**
(45) **Date of Patent:** **** Aug. 13, 2024**

(54) **FITTING FOR HYDRAULIC SANITARY EQUIPMENT**

(71) Applicant: **Oventrop GmbH & Co. KG**, Olsberg (DE)

(72) Inventors: **Marius Funke**, Bestwig-Ostwig (DE); **Holger Wienand**, Olsberg-Bruchhausen (DE); **Sven Feustel**, Stuttgart (DE)

(73) Assignee: **OVENTROP GMBH & CO. KG**, Olsberg (DE)

(**) Term: **15 Years**

(21) Appl. No.: **35/513,991**

(22) Filed: **Dec. 23, 2021**

(80) **Hague Agreement Data**

Int. Filing Date: **Dec. 23, 2021**

Int. Reg. No.: **DM/219872**

Int. Reg. Date: **Dec. 23, 2021**

Int. Reg. Pub. Date: **Apr. 8, 2022**

(30) **Foreign Application Priority Data**

Jun. 30, 2021 (DE) 402021100577

(51) **LOC (14) Cl.** **23-07**

(52) **U.S. Cl.**

USPC **D23/259**; D23/262; D23/263

(58) **Field of Classification Search**

USPC D23/259, 262, 266, 233, 235, 245, 250, D23/260, 263-265, 268

(57) **CLAIM**

The ornamental design for a fitting for hydraulic sanitary equipment, as shown and described.

DESCRIPTION

Fig. 3.1 is a perspective view;

Fig. 3.2 is a side view;

Fig. 3.3 is a front view; and

Fig. 3.4 is a top view.

The broken lines depict portions of the fitting for hydraulic sanitary equipment that form no part of the claimed design. The dot dash dot lines denotes the boundary of the claim and forms no part thereof.

1 Claim, 4 Drawing Sheets
